CAR COUPLER

William J. Metzger, Cleveland, Ohio, assignor to
National Malleable and Steel Castings Com-
pany, Cleveland, Ohio, a corporation of Ohio

Application July 23, 1938, Serial No. 220,864

10 Claims. (Cl. 213—127)

This invention relates to car couplers, and more particularly pertains to means for positively preventing undesired movement of the lock from locked to unlocked position. The invention comprises certain novel improvements over the form of anti-creep means shown in copending Bazeley application Serial No. 71,414, filed March 28, 1936.

It is well known that due to the weaving action of adjacent cars when in motion, forces are exerted on the lock by the knuckle which tend to cause the lock to creep upwardly. This is particularly true where the locking faces on the knuckle and lock are at a slight angle to the vertical, such a lock commonly being known as a wedge lock, but is also true in other types of locks having vertical locking faces.

An object of my invention is to make the anti-creep means effective for limiting undesired vertical movement of the lock by forming means on a part of the lock operating mechanism for preventing the leg of the lock from working out from beneath the anti-creep ledge on the coupler head.

A further object of my invention is the provision of anti-creep means as above described, which, however, can be readily disengaged by the operating mechanism so that the lock may be raised for unlocking the knuckle.

Other objects and advantages of my invention will be more fully understood from the following description in conjunction with the drawings, in which:

Figure 1 is a vertical sectional view through a portion of a car coupler embodying my invention.

Figure 2 is a vertical sectional view, taken generally along the line 2—2 of Fig. 1.

Figure 3 is a view of the bottom portion of Fig. 1, with the lock moved vertically until the anti-creep means are engaged.

Figure 4 is a partial view in vertical section, showing the operation of the uncoupling means in disengaging the anti-creep means; and

Figure 5 is a view similar to Fig. 4, showing the position of the parts just after the anti-creep means between the lock leg and coupler having been disengaged.

In the drawings, the knuckle 11 is pivoted to coupler head 10 for movement in a horizontal plane. A lock 12 has a sloping surface 13 adapted to engage a corresponding face 14 on the tail of the knuckle for locking the knuckle in closed position. The opposite side of the lock engages wall 15 of the coupler for resisting pivotal movement of the knuckle. As shown in Fig. 2, the lock is first fitted in the coupler in a slightly raised position, so that there is some clearance

between the overhanging ledge 16 on the lock and a shelf 17 on the knuckle tail permitting further downward movement of the lock relative to the knuckle for a limited amount of takeup, which may occur as the result of wear of the parts. A second ledge 18 on the knuckle tail may be similarly spaced from surface 19 on the lock for limiting vertical downward movement of the lock. An opening 20 in the bottom of the coupler head normally receives the leg 21 of the lock when the latter is in locked position. Projecting forwardly from the bottom of leg 21 is an anti-creep shoulder 22 adapted to normally underlie ledge 23 on the coupler head at the forward end of opening 20.

The operating mechanism for raising the lock comprises a link 24 having an angularly disposed opening 25 which receives a lateral projection 26 on the lock. The bottom of link 24 is bifurcated to form arms 27 and 28 between which is positioned the end 29 of uncoupling lever 30. A rivet 31 pivotally joins the lever with link 24. The other end of lever 30 is formed with a hook-shaped portion 32 pivotally supported on a member 33 on the coupler head to the rear of the lock. Intermediate its ends link 30 is formed with an opening 34 which receives a member 35 extending between link 30 and a bail 36. The bail is pivotally supported on brackets 37 on the underside of the car structure and is rotated forwardly and upwardly by means of uncoupling rod 38.

Upon actuation by the uncoupling rod through bail 36 and member 35, lever 30 is pivoted forwardly and upwardly, causing lower wall 40 of slot 25 in link 24 to slide along projection 26 thus moving leg 21 of the lock from beneath the anti-creep ledge 23 of the coupler. When the lower end of slot 25 is engaged with projection 26, further pivotal movement of lever 30 will move link 24 and hence the lock vertically until the lock reaches its unlocked position.

Under actual service conditions it has been found that the lock may move, due to the weaving action of the cars, so as to rotate the leg thereof rearwardly, tending to destroy the overlap between the anti-creep shoulder on the lock and the anti-creep ledge on the coupler head. During this movement projection 26 on the lock exerts a camming action against upper surface 41 of slot 25, causing link 24 to move vertically. Since, as previously explained, the anti-creep means comprising shoulders 22 and 23 no longer overlap each other when the bottom of slot 25 engages projection 26, the aforesaid camming action will, if not prevented, permit the anti-

creep means to become disengaged at just the time when it is intended that it be effective. In my invention, I provide stop means between the coupler head and a portion of link 24 to limit vertical movement of the link during the aforesaid camming action between projection 26 and surface 41. This means comprises a forwardly and upwardly sloping shoulder 42 formed on the rear of link 24 and adapted when the link is moved rearwardly to underlie a similarly sloped surface 43 on the coupler head. Rearward movement of leg 21 of the lock will therefore, as it moves link 24 rearwardly, cause an overlap between surfaces 42 and 43, thus preventing vertical movement of link 24 and hence the lock relative to the coupler head.

Fig. 3 shows the position of the parts after the lock has moved vertically until shoulder 22 has engaged ledge 23 at the same time the leg 21 of the lock has moved rearwardly in the direction that would disengage the anti-creep. However, it will be observed that the above described movement causes contact between surfaces 42 and 43 which effectively prevents either rearward or upward vertical movement of the lock leg relative to the coupler. The lock can not exert a camming action against surface 41 that would move link 24 vertically since the latter is held against vertical movement by engagement between surfaces 42 and 43. It will be understood that in positions of the lock intermediate those shown in Figs. 1 and 3 rearward movement of the lock leg such as would cause shoulder 22 to move from beneath ledge 23 would effect engagement between surfaces 42 and 43 to prevent further vertical movement of the lock.

In addition to contact between surface 40 and projection 26, withdrawal of shoulder 22 from ledge 23 is made possible by reason of the fact that end 29 of lever 30 moves forwardly and upwardly so that the center of projection 26 is rearwardly of a line drawn through the center of rivet 31 and approximately the center of rotation of the lock, thus the toggle between the lock and link 24 is broken rearwardly so that as lever 30 is further rotated forwardly and upwardly projection 26 on the lock is caused to move rearwardly until shoulder 22 is entirely withdrawn from beneath shelf 23.

Surfaces 42 and 43 should be at such an angle to the vertical that when link 24 is actuated by lever 30 the aforementioned surfaces can readily slide upon each other so as to be disengaged during uncoupling of two couplers. I have found that an angle substantially the same as the slope of slot 25 in link 24, when the latter is in normal position, gives very satisfactory results. At the same time such an angle is sufficient to prevent surface 42 from slipping past surface 43 during creeping of the lock.

In Figs. 4 and 5 two positions of the various parts are shown during the withdrawal of shoulder 22 from beneath ledge 23 when the lock has moved upwardly sufficiently for the anti-creep to engage. The first movement of link 24 upwardly causes surface 42 thereon to slide from beneath surface 43 on the coupler. On the forward wall 45 of the coupler and adjacent ledge 23 there is formed a projection 46 adapted to be engaged by forward surface 47 on link 24 to force the upper end of the latter rearwardly when the link is moved upwardly during an uncoupling operation. Since the upper end of link 24 is moving rearwardly, and inasmuch as projection 26 is being moved rearwardly by surface 40, the

resultant effect will be that the lock leg is withdrawn from beneath ledge 23. This movement further acts to break the toggle, as previously described, thus positively assuring withdrawal of the lock leg from beneath the anti-creep ledge. 5 In Fig. 5 the lock is shown moved rearwardly and entirely disengaged from ledge 23 and in this position of the parts the surface 47 of the link has been moved, due to the breaking action of the toggle, until it no longer engages projection 10 46 of the coupler head.

It will be observed, particularly in Figs. 3 and 4, that ledge 23 extends downwardly and rearwardly a slight amount so that there is no tendency for shoulder 22 when in engagement with the ledge to slip out from beneath the ledge upon an upward force being directed against the lock.

The terms and expressions which I have employed are used as terms of description and not 20 of limitation, and I have no intention, in the use of such terms and expressions, of excluding any equivalents of the features shown and described or portions thereof, but recognize that various 25 modifications are possible within the scope of the invention claimed.

What I claim is:

1. In a car coupler having an opening in the bottom thereof, a lock adapted to move vertically and having a leg extending into said opening, 30 means on said leg adapted to underlie a portion of said coupler forwardly of said lock for limiting upward movement of said lock, uncoupling means pivoted to said coupler and shiftably connected with said lock for moving the latter vertically, and means on said uncoupling means adapted to underlie a portion of said coupler rearwardly of said lock for preventing undesired withdrawal of said first named means from beneath said leg. 40

2. In a car coupler, a vertically movable lock having a downwardly extending leg, a rotor lift lever pivotally mounted on the bottom of said coupler to the rear of said lock, a link shiftably connected with said lever and the leg of said lock, disengageable anti-creep means comprising a projection on said leg underlying a stop on said head, and means on said link underlying a portion of said coupler head for normally preventing disengagement of said anti-creep means without preventing operation of said link by said lever. 45

3. In a car coupler, a lock having a leg extending downwardly into an opening in the bottom of said coupler, a lever pivoted on said coupler to the rear of said opening, a link shiftably connected with said lever and lock, a lug on said coupler extending into one end of said opening and adapted to cooperate with a portion of said lock to limit upward movement thereof, and means adjacent the opposite end of said opening adapted to cooperate with said link for limiting upward movement thereof by said lock relative to said coupler. 55

4. In a car coupler, a lock member having a leg extending downwardly into an opening in the bottom of said coupler, a lever pivoted on said coupler to the rear of said opening, a link member joining said lever and lock member and shiftable with respect to said lock member, a lug on said coupler extending into one end of said opening and adapted to cooperate with a portion of one of said members to limit upward movement thereof, and means adjacent the opposite end of said opening adapted to cooperate with the other of said members for limiting up- 75

- ward movement thereof by said one of said members relative to said coupler.
5. In a car coupler including a knuckle and a lock, a lever pivotally mounted on the bottom of said coupler to the rear of said lock, a slotted link shiftably connected with said lever and the bottom of said lock, said lock having a projection extending into the slot in said link, said lock underlying a portion of said coupler to form an anti-creep and means comprising a portion of said link adapted to underlie a part of said coupler head for preventing said anti-creep from becoming ineffective.
6. In a car coupler having an opening in the bottom thereof, a knuckle, a member for locking said knuckle in closed position, said member having a portion extending into said opening, operating means shiftably connected to said portion for moving said member vertically for unlocking said knuckle, disengageable means for preventing undesired vertical movement of said member to knuckle unlocking position, and means comprising portions of said operating means adapted to underlie a part of said coupler 25 for normally maintaining said disengageable means in position for preventing said undesired vertical movement.
7. In a car coupler including a knuckle and a lock, a lever pivotally mounted on the bottom of said coupler to the rear of said lock, a link having a forwardly and upwardly sloping slot connecting said lever and the bottom of said lock, said lock having a projection extending into said slot and slidably relative thereto, said lock underlying a portion of said coupler to form an anti-creep, said link having a forwardly and upwardly sloping surface adapted to underlie a corresponding surface on said coupler for preventing said anti-creep from becoming ineffective.
8. In a car coupler including a knuckle and a lock, a lever pivotally mounted on the bottom of said coupler to the rear of said lock, a link having a forwardly and upwardly sloping slot connecting said lever and the bottom of said lock, 5 said lock having a projection extending into said slot, said lock underlying a portion of said coupler to form an anti-creep, said link having a forwardly and upwardly sloping surface adapted to underlie a corresponding surface on said coupler for preventing said anti-creep from becoming ineffective, said surfaces having substantially the same slope as said slot.
9. In a car coupler including a knuckle and a lock member, a link member connected to said lock member and constructed and arranged for horizontal and vertical displacement relative thereto, means for actuating said link member for lifting said lock, and anti-creep means on said members adapted to underlie spaced portions of 20 said coupler to limit upward movement of said lock, said anti-creep means being disengageable upon relative horizontal displacement of said members when the latter are moved by said actuating means.
10. In a car coupler including a knuckle and a lock means for raising said lock including a link member, said link being joined with said lock in such a manner as to be horizontally displaceable relative thereto, said lock and link underlying spaced portions of said coupler under conditions of maximum relative horizontal displacement thereof to form an anti-creep means for said lock, and said link being adapted to move to a position of minimum horizontal displacement 30 relative to said lock to disengage said anti-creep means when actuated by said lock raising means.

WILLIAM J. METZGER.
